US0D1008793S

(12) **United States Design Patent** (10) **Patent No.:** **US D1,008,793 S**
(45) **Date of Patent:** **** Dec. 26, 2023**

(54) **FURNITURE FITTING**

(71) Applicant: **Julius Blum GmbH**, Hoechst (AT)

(72) Inventor: **Olaf Isele**, Lustenau (AT)

(73) Assignee: **JULIUS BLUM GMBH**, Hoechst (AT)

(**) Term: **15 Years**

(21) Appl. No.: **29/823,699**

(22) Filed: **Jan. 19, 2022**

(30) **Foreign Application Priority Data**

Jul. 20, 2021 (EM) 008623581-0006

(51) **LOC (14) Cl.** **08-11**

(52) **U.S. Cl.**

USPC **D8/377**; D8/380; D8/400

(58) **Field of Classification Search**

USPC D8/349, 354, 380, 381, 374, 377, 400
